UNITED STATES PATENT OFFICE.

SAMUEL W. LUITWIELER, OF ROCHESTER, NEW YORK.

CAM-DRIVEN PUMP.

Application filed September 27, 1922. Serial No. 590,858.

To all whom it may concern:

Be it known that I, SAMUEL W. LUITWIELER, a citizen of the United States of America, residing at Rochester, in the county of Monroe and State of New York, have invented certain new and useful Improvements in Cam-Driven Pumps, of which the following is a specification.

My invention relates to a cam driven pump, and embodies various improvements over the types of pumps disclosed in my prior Patents No. 819,295, patented May 1, 1906, and No. 926,267, patented June 29, 1909.

In a more particular aspect, this invention has for its purpose to afford a cam driven pump especially adapted to deep well work, although susceptible of other uses, and with which a water column can be kept in motion continuously at constant volume and under constant pressure, without the necessity of any air chamber, and in such a manner as to practically eliminate vibration or pulsation, giving an approximately steady flow of water.

Another object of the improvement is to afford a pump of the general type set forth, embodying a frame characterized by extreme strength and stiffness, and arranged so that the structure can be manufactured and assembled at a low cost, and having the additional advantage of not being affected as to efficiency or proper operation by wear of the parts.

With these ends in view, the invention includes the novel arrangement that will appear clearly from the following description, in conjunction with the accompanying drawings, the novel feature being pointed out in the claims following the specification.

In the drawings:

Figure 1 is a side elevation of a pump embodying a preferred arrangement of my invention, the frame being partially broken away;

Figure 2 is a plan view of the parts appearing in Figure 1, with a portion of the frame broken away at the top;

Figure 3 is a vertical sectional view on line 3-3 of Figure 1;

Figure 4 is a horizontal sectional view on line 4-4 of Figure 1;

Figure 5 is a side elevation of the cam, showing in diagram the cooperating rollers, and the system according to which the cam is laid out;

Figure 6 is a central sectional view of the cam, and

Figure 7 is a diagram illustrating the relation between the cam and the work to be performed.

Referring more particularly to the drawings in which like reference numerals correspond to similar parts in the several views, the structure comprises a frame which includes a base 1 and integral columns or standards 2 arranged at the sides of the base and forwardly thereof, while 3 designates a top member which is of general U-shaped contour, and formed integral with the columns 2.

The top member 3 extends rearwardly from the columns 2 and the frame is braced at the front and top by an integral connecting front plate 4. Arranged between 75 and secured to the base 1 and top member 3 of the frame are front guide-rods 6, disposed outwardly of the cams to be mentioned presently, and rear guide-rods 7 disposed between said cams, and on said guide-rods 80 travel the cam frames, also to be described presently. The cam-shaft is designated at 8, being journalled in suitable fixed bearings 9 of the frame and having fixed thereon a gear 10 engaged and driven by a pinion 11 on the pulley shaft 12 to which power is furnished through the pulley 13 or otherwise.

It is highly important and essential to proper efficiency of such a pump that the 90 guide-rods be effectively braced at points intermediate their tops and bottoms. To accomplish this, I have provided bracing members embodying lugs 14 carried by and preferably formed integral with the columns 2 at points about midway between the top and bottom of the frame, said lugs 14 having vertical openings through which the guide-rods 6 are inserted in assembling, and by tying these guide-rods at their centers in the manner just described, they are held effectively against the slightest lateral strain and afford an absolutely rigid guide for the cam frames. In order to similarly brace the rear guide-rods 7, I 105 employ a bracing member consisting of a bracket or yoke 15 supported on the cam-shaft 8, as shown in Figure 4, by means of an opening through which said cam-shaft passes, and having recesses or pockets 110 embracing the guide-rods 7. The bracket 15 is held in rigid engagement with the guide-

rods 7 by means of a removable locking plate 16, thus affording a simple, economical, and practical means for rigidly bracing the rear guide-rods 7 at a point intermediate 5 their tops and bottoms.

In the pump disclosed, there are two cams oppositely arranged and fixed upon the cam-shaft 8, and each cooperating with rollers at the top and bottom of a separate cam frame. Referring to Figure 1, the upper cam A cooperates with rollers at the top and bottom of a cam frame that is attached to and operates a solid pump rod 17, while the lower cam B cooperates with 10 rollers at the top and bottom of a cam frame that is connected to and operates a hollow pump rod 18 surrounding the solid pump rod 17, said solid and hollow pump rods being connected to pistons which are 15 located sufficiently far apart in the working cylinder to permit the necessary alternating stroke, as well known in this type of pump. To accomplish this, the hollow pump rod 18 is secured by means of a split 20 collar 19 which is bolted to the pump rod and is carried by the cross-head 20 of the corresponding cam frame, while the solid pump rod 17 passes through an opening in a lug 21 that is carried by the cross-head 25 30 of the corresponding cam frame.

The cross-head 20 carries a cam-engaging roller and is connected by vertical tie-rods 23 to an upper cross-head 24, which also carries a cam-engaging roller, said tie-rods 35 being fixed to the lower cross-head and extending through openings in the upper cross-head and adjustably held in engagement therewith by means of nuts on opposite sides of the cross-head. This permits of 40 readily and accurately adjusting the cam frames and rollers to the periphery of the cam. The cross-heads 20 and 24 are provided with integral guide loops 25 and 26 which travel on the front and rear guide- 45 rods 6 and 7 respectively, while the cross-head 22, carrying a cam-engaging roller, is similarly connected by tie-rods 27 with a cross-head 28, also carrying a cam-engaging roller, said cross-heads 22 and 28 having 50 guide loops 29 and 30 sliding on the corresponding front and rear rods 6 and 7. The cam A, as it rotates, operates the cam frame embracing the cross-heads 22 and 28, while cam B operates the cam frame embracing the 55 cross-heads 20 and 24, and I will now describe the novel characteristics of the cam that I employ for effecting the necessary movements of the cross-heads.

Figures 5 to 7 illustrate the peripheral outline of the cam and the method of laying it out. The cam is of symmetrical form, and so designed as to produce an approximately constant discharge of liquid at all times. To accomplish this, it is necessary 60 that the cam frames travel uniformly 65

throughout practically their entire path of movement, and this is effected in the present structure by having the effective contour of the cam of a uniformly increasing distance from the axis of the cam.

In Figure 7, the inclined straight line x represents the discharge of water and is a constant factor, the horizontal line y represents the starting point of the cam, and the vertical lines z represent the constantly increasing distances of the cam surface from the axis of the cam. Referring to Figure 5, starting with the fixed points, including the cam axis a , and the centers b , c , of the rollers which engage the cam periphery, the 70 contour of the cam is obtained by first striking the various radial lines d which are equal distances apart measured on a concentric circle b e . The centers f for striking the arcs from which to chart the cam, 75 are then established by measuring on each radial line d a distance beyond the circle b e equal to the length of the corresponding line z in Figure 7. Then by striking a series of arcs about centers f with a radius 80 equal to the radius of the roller, points are found which establish the curve of the cam. As a matter of working practice, it is desirable to provide the cam with a flat base, 85 and to flatten out the cam at its outermost 90 point instead of letting the curve run to a sharp point, in order to afford a continuous curve, and the effect of this is illustrated by the curved line g g' in Figure 7. While this results in a slightly decreased movement of 95 the cam frame when the outermost point of the cam is operating, the speed of travel is correspondingly increased, owing to the greater distance from the center of the cam, 100 and the liquid being discharged at this increased speed carries the stream, and bridges what would otherwise be a gap between the successive action of the cams.

While I have described the invention as applied to a particular embodiment, it is 110 not limited to the precise arrangements or details herein disclosed, but this application is intended to cover any modifications or departures from the mechanism set forth that may come within the intended purposes 115 of the invention or the scope of the following claims.

I claim:

1. In a pump, the combination with a cam-shaft and cam fixed thereon, of a cam frame including upper and lower cross-heads carrying rollers engaging the cam at opposite points of its periphery, a front guide-rod disposed at one side of said cam, a rear guide-rod disposed at the opposite 125 side of the cam, and guide loops carried by said cross-heads and travelling on the guide-rods.

2. In a pump, the combination with a cam-shaft and cam fixed thereon, of a cam 130

frame including upper and lower cross-heads carrying rollers engaging the cam at opposite points of its periphery, tie-rods carried by one of said cross-heads and adjustably connected to the other of said cross-heads, guide-rods for the cam frames, and guide loops carried by the cross-heads and travelling on said guide-rods.

3. In a pump, the combination with a cam-shaft and cam fixed thereon, of a cam frame including upper and lower cross-heads carrying rollers engaging the cam at opposite points of its periphery, tie-rods carried by one of said cross-heads and adjustably connected to the other of said cross-heads, a front guide-rod disposed at one side of said cam, a rear guide-rod disposed at the opposite side of the cam, and guide loops carried by said cross-heads and travelling on the guide-rods.

4. In a pump, the combination with a cam-shaft and a cam fixed thereon, of a frame including a base, a vertical column, and a top member, guide-rods secured between the base and top member, a bracing member carried by said column intermediate its base and top member and embracing one of said guide-rods, and a cam frame movable on said guide-rods and carrying rollers engaging the cam at opposite points.

5. In a pump, the combination with a cam shaft and a cam fixed thereon, of a frame including a base, vertical columns, and a top member, guide-rods secured between the base and top member, a bracing member supported by said cam-shaft and embracing one of said guide-rods at a point intermediate the base and top member, and a cam frame movable on said guide-rods and carrying rollers engaging the cam at opposite points.

6. In a pump, the combination with a cam-shaft and a pair of cams fixed thereon, of a frame including a base, vertical columns, and a top member, front and rear guide-rods secured between the base and top member, bracing members carried by the columns intermediate the base and top member and embracing said front guide-rods, a bracing member supported by said cam-shaft and embracing said rear guide-rods at a point intermediate the base and top member, and cam frames movable on said guide-rods and carrying rollers engaging the cams at opposite points.

7. In a pump, the combination with a

cam-shaft and a pair of cams fixed thereon, of a frame including a base, vertical columns, and a U-shaped top member, front and rear guide-rods secured between the top member and base, the front guide-rods being located outwardly of said cams and the rear guide-rods being located between the cams adjacent to the center of the U-shaped top member, bracing members carried by the columns intermediate the base and top member and embracing said front guide-rods, a bracing member supported by said cam-shaft and embracing said rear guide-rods at a point intermediate the base and top member, and cam frames movable on said guide-rods and carrying rollers engaging the cams at opposite points.

8. In a pump, the combination with a cam-shaft and a pair of cams fixed thereon, of a frame including a base, vertical columns, and a U-shaped top member, front and rear guide-rods secured between the top member and base, the front guide-rods being located outwardly of said cams and the rear guide-rods being located between the cams adjacent to the center of the U-shaped top member, bracing lugs formed integral with the columns intermediate the base and top member and embracing said front guide-rods, a bracing member supported on said cam-shaft and including a removable plate embracing said rear guide-rods at a point intermediate the base and top member, a bracing plate connecting the tops of said columns at the front and formed integral therewith, and cam frames movable on said guide-rods and carrying rollers engaging the cams at opposite points.

9. In a pump, the combination with a cam shaft, of two reversible double-acting cams oppositely fixed thereon and a pair of cam frames cooperating with the cams and connected to a pair of pump rods, each of the cams being symmetrical with a flat base and continuously curved outer end and acting during each 180° of turning to effect an active stroke of its pump rod in one direction, each cam being so formed as to effect a uniform movement of its pump rod in both directions and produce a liquid discharge of substantially constant volume and pressure.

In witness whereof, I have hereunto signed my name.

SAMUEL W. LUITWIELER.
